UNITED STATES PATENT OFFICE

156,035

DESIGN FOR A MARBLE SHOOTING APPARATUS

Walter E. Richardson, Chicago, Ill.

Application January 26, 1948, Serial No. 144,039

Term of patent 3½ years

(Cl. D34—15)

To all whom it may concern:

Be it known that I, Walter E. Richardson, a citizen of the United States and a resident of 2552 Eastwood Avenue, Chicago, in the county of Cook and State of Illinois, have invented a new, original, and ornamental Design for a Marble Shooting Apparatus, of which the following is a specification, reference being had to the accompanying drawing, forming a part thereof, and in which:

Fig. 1 is a side elevational view of a marble shooting apparatus showing my new design;

Fig. 2 is a front elevational view of the same; and

Fig. 3 is a rear elevational view of the same.

I claim:

The ornamental design for a marble shooting apparatus, as shown.

WALTER E. RICHARDSON.
